CONSISTENCY REGULATOR

Hervey G. Cram, Appleton, Wis., assignor to P. D. Cram, Appleton, Wis.

Application May 26, 1938, Serial No. 210,141

4 Claims. (Cl. 265—11)

This invention appertains to a novel device for regulating the consistency of pulp or stock for use in the making of paper or similar fibrous products.

One of the primary objects of my present invention is to provide a regulator which will quickly and accurately respond to any change in the consistency of the pulp and rectify said change rapidly without any appreciable time lag between the delivery or checking, as the case might be, of the dilution liquid and its effect upon the regulator, so that a uniform consistency of the stuff or pulp passing through the stuff gate will be had.

Another salient object of my invention is to provide a consistency regulator of a compact and durable construction which can be placed adjacent or directly on the stuff regulator box, so that the stuff flowing through the stuff gate of the box will act immediately on the consistency regulator.

A further important object of my invention is the provision of a flexible diaphragm in the consistency regulator and a head located directly over an orifice in the regulator and at right angles to the direction of flow of the stuff or stock through the regulator and above the diaphragm, whereby with an increase in the consistency of the stock, the rate of flow of the stock will be retarded at the orifice by the head, and thus effect an increase in pressure on the diaphragm, the movement of the diaphragm effecting operation of the liquid dilution control valve.

A still further object of my invention is the provision of means for adjusting the position of the head relative to the orifice, whereby a desired selective consistency of stock can be maintained.

A still further object of my invention is to provide a novel arrangement of diaphragms in the consistency regulator, with means operating in conjunction with the diaphragms for visually indicating the pressure on the diaphragms and the condition of said diaphragms.

With these and other objects in view, the invention consists in the novel construction, arrangement, and formation of parts, as will be hereinafter more specifically described, claimed, and illustrated in the accompanying drawings, in which drawings:

Figure 1 is a view partly in elevation and partly in section, showing the use of my improved consistency regulator.

Figure 2 is a view taken substantially on the line 2—2 of Figure 1, looking in the direction of the arrows.

Figure 3 is a top plan view of the adjustable head of the regulator and the position of the stationary scale relative to said head.

Figure 4 is a detail sectional view through the dilution control valve, the view being taken substantially on the line 4—4 of Figure 2, looking in the direction of the arrows.

Referring to the drawings in detail wherein similar reference characters designate corresponding parts throughout the several views, the letter R generally indicates my improved consistency regulator, and B a stuff regulator box with which the same is associated.

The stuff regulator box B is provided at one side with a stock outlet opening 5, the active size of which is controlled by a sliding gate 6. The gate can be raised and lowered in any preferred manner from the top of the box, as shown, to open and close the opening 5.

Arranged within the box B is a vertically extending partition 7. The stock is delivered into the box on one side of the partition 7 by means of a pipe 8, which leads from a pump 9. The pump 9 receives the stock from the stuff tank 10. Obviously, this tank can be provided with an agitator, if so desired, and the stock is received into the tank from any suitable source of supply. Communicating with the box B on the other side of the partition 7 from the delivery pipe 8 is a stock return pipe 11, which leads back to the stuff tank 10. The partition 7 maintains a desired and constant head in the box B, so that the pressure will be the same at all times at the opening 5. A relatively short baffle 12 is arranged in the box B in front of the delivery pipe 8. This baffle 12 serves a dual function: first, to prevent incident effect of wild currents from the inlet of pipe 8 upon the flow of pulp through the gate opening 5; second, to split the direction of flow of the stock. Thus, a part of the pulp is directed over the partition 7, and a part toward the gate opening 5.

My novel consistency regulator R comprises a body 15, which can be of a cylindrical shape, as shown. One side of the body is provided with a radially extending inlet collar 16. This collar carries a flange 17, by means of which the regulator can be bolted directly to the stuff regulator box B around the opening 5. Thus, the stock flows directly from the box B into the regulator body 15.

The upper end of the regulator body 15 has secured thereto a dome 18, and arranged between the dome and the body 15 and secured in

place by the bolts of the dome is a plate 19. This plate 19 extends entirely across the upper end of the body 15 and is provided with an axially disposed outlet opening or orifice 20. Adjustably mounted in the dome 18 is the regulator head 21. The head 21 is provided with relatively fine exterior threads for engaging similar interior threads carried by the dome, whereby the head can be accurately adjusted relative to the outlet orifice 20. By moving the head 21 toward and away from the opening 20, the rate of flow of stock through the opening 20 can be controlled.

The head is provided with an outstanding annular flange 22, and this flange can carry suitable handles 23, whereby the head can be conveniently turned. This flange is also graduated, and the graduations on the flange cooperate with graduations 25 on a rule rod 26 for indicating the exact position of the head 21 relative to the opening 20. The rod 26 is securely bolted to the dome in any preferred manner.

Extending radially from the dome 18 above the plate 19 is the outlet collar 27, and this collar has bolted thereto an outlet stock pipe 28. This pipe can lead to the point of use of the pulp. If desired, the plate 19 can carry an arcuate, upstanding guide wall 29 for engaging the adjustable head 21, and as this wall 29 is located diametrically opposite the outlet collar 27, the wall tends to direct the stock or stuff toward said outlet collar.

The lower end of the body 15 is closed by a flexible inner diaphragm 30, and this diaphragm 30 is held in place by a ring 31. A second diaphragm 32 is securely fastened to the ring 31 by a second ring 33, and the ring 31 spaces the inner and outer diaphragms 30 and 32 one from the other, and thus a compartment 34 is formed between the diaphragms. The space between the diaphragms is filled with water or other desired fluid, for a purpose which will be set forth later. It can be seen, however, that movement of the inner diaphragm 30 will be transmitted to the outer diaphragm 32. Movement of the diaphragms controls the dilution of the stock in the stuff regulator box by means which will now be set forth.

Depending from the bottom ring 33 is a pair of bracket arms 35, which rotatably support an operating shaft 36. The central part of the shaft has formed thereon or secured thereto a crank-arm 37, and this crank-arm, in turn, has pivotally connected thereto an upstanding rod 38, which bears against a pressure plate 39. This pressure plate snugly engages the lower diaphragm 32 and, thus, movement of the diaphragm will be transferred to the shaft 36 through the medium of the rod 38 and crank-arm 37. In order to support the pressure plate, the same has formed thereon or secured thereto depending ears 40, which are pivotally mounted on links 41. These links are, in turn, mounted upon the cross-shaft 42, carried by the main bracket arms 35.

Extending into the stuff regulator box B is the dilution liquid pipe 43. This pipe is provided with an outlet head 44 directly above the stuff outlet opening 5. Arranged within the length of the pipe 43 adjacent one of the bracket arms 35 is a control valve 45. The valve can be securely fastened to the body 15 by means of a bracket 46. The valve 45 is shown in detail in Figure 4 of the drawings. The specific construction of the valve itself forms no part of the present invention, and

will not be described in detail, but it is to be noted that the same includes a vertically movable valve stem 47, and that this stem has pivotally connected thereto a link 48. The link, in turn, is pivotally connected to a crank 49 securely fastened to one end of the operating shaft 36. If desired, a packing box can be carried by the valve casing for the shaft 36.

The end of the shaft 36 remote from the valve 45 has mounted thereon a clamp 50. This clamp 50 receives a rod 51, and a weight 52 of the desired mass is adjustably mounted on the rod. The weight is movable toward and away from the shaft 36 and projects from the shaft in a direction opposite to the crank-arm 37. The weight 52 holds the pressure plate 39 against the lower diaphragm 32, and, obviously, by adjusting the weight on the rod 51 toward and away from the shaft 36, the pressure leverage plate can be held with the desired pressure against the diaphragm.

A depending rod 55 is also carried by the clamp 50, and an adjustable weight 56 is mounted on the rod 55. The function of the vertical weight 56, as positioned on the rod 55, is to allow adjustment of the speed of the valve opening with relation to the change in the head across the stuff box opening 5, as effected by a consistency change.

In the operation of my regulator, the stuff is supplied to the regulator box B through the pipe 8, and a uniform head is maintained in the box by the partition 7. The gate 6 is adjusted to the desired position, as is the regulator head 21. The stock flows from the opening 5, through the regulator, and out of the pipe 28. As the stock leaves the regulator, the same flows through the orifice 20 and impinges against the head 21. It is to be noted that the head is disposed at direct right angles to the direction of flow of the stock, and consequently the stock makes a substantially right-angled turn above the orifice. Initially, the weight 52 and the valve 45 are set to regulate a small, but desired flow of dilution liquid to the box B.

With an increase in the consistency of the stock flowing through the regulator, the rate of flow will be retarded at the orifice 20, which effects an increase in pressure on the diaphragms 30 and 32. The movement of the diaphragms will rotate the shaft 36, and consequently operate the valve 45 for increasing the flow of dilution liquid to the stock. Obviously, with a decrease in consistency of the stock, the pressure on the diaphragms will be decreased, and consequently the valve 45 will be operated to decrease the flow of dilution liquid to the stock.

As the pressure in the regulator increases as affected by the frictional action at the orifice 20, the differential in the head across the opening 5 is decreased correspondingly, with the result that the flow through the opening 5 is decreased, and the rate of flow of solid paper-making material remains practically constant.

The rate of flow of dilution liquid through the valve 45 with relation to the variation in the head across the opening 5, resulting from consistency variation, is determined by the vertical position of the weight 56 on the rod 55. As the regulator is located directly at the stuff regulator box, and as the regulator is extremely sensitive, the delivery of the dilution liquid is practically instantaneous with the operation of the diaphragms, and consequently time lag is practically eliminated between the time of delivery of the dilution

it effect upon the dia-

The weight of the sheet of paper made from the pulp is determined by the area of the opening 5 (determined by the vertical position of the gate 6) and the relative area of the orifice 20 (determined by the vertical position of the adjustable head 21). It is to be noted that the outlet head 44 is disposed between the baffle 12 and the front of the box 5. Thus, the dilution liquid is admitted to the pulp that is flowing toward the opening 5. Therefore, the pulp being returned to the tank 10 is not affected by the dilution liquid.

The diaphragms 30 and 32 are preferably made from rubber, although obviously other material can be used. As the chamber 34 between the diaphragms can be filled with water, the opposite faces of the diaphragm 30 remain wet at all times, and this insures long life to the inner diaphragm.

Visual change in the position of the diaphragms is shown in the sight glass 53, and this glass communicates with the chamber 34 by means of a pipe or tube 54. Obviously, rupture of either one of the diaphragms 30 or 32 will be immediately shown in the sight tube by the raising and lowering of the liquid therein.

From the foregoing description it can be seen that I have provided a precision consistency regulator for paper stock, which is of a compact and durable construction, and which can be associated directly with the stuff regulator box.

Changes in details may be made without departing from the spirit or the scope of the invention, but what I claim as new is:

1. A consistency responsive apparatus for pulp comprising, a box for the pulp having a discharge opening maintained under a constant head of pulp, a body for receiving pulp directly from said opening, said body having an axial orifice therein through which the pulp travels, a head in said body arranged directly above the orifice and having a surface which extends at right angles to the direction of flow of pulp through the orifice, and so positioned as to cause a resistance to the flow of the pulp and a pressure, a diaphragm in said body responsive to change in pressure caused by change in consistency of the pulp acting on said head, and an operating mechanism actuated by the diaphragm and responsive to the pressure on the diaphragm caused by the change of consistency in the pulp.

2. A consistency responsive apparatus for pulp

comprising, a box having a discharge outlet maintained under a constant head of pulp, a body disposed exteriorly of the box having an inlet for receiving the pulp from said opening and a discharge outlet, said body having an orifice therein between the inlet and outlet through which the pulp flows, a diaphragm on one side of the orifice, means on the other side of the orifice to cause a frictional resistance to the flow of the pulp and create pressure on the diaphragm, the diaphragm being movable under the variation of pressure caused by the change of consistency in the pulp, said means being adjustable toward and away from the orifice for controlling the rate of flow of pulp through the orifice, and an operating mechanism actuated from the diaphragm and responsive to the pressure on the diaphragm caused by the change of consistency in the pulp.

3. A consistency responsive apparatus for pulp comprising, a body having an inlet opening for pulp and a discharge opening for pulp, said body having an orifice between said openings through which the pulp flows, a diaphragm on one side of the orifice, a head mounted in said body on the other side of the orifice and adjustable toward and away from the orifice to cause a frictional resistance to the flow of pulp through the orifice and a pressure from the pulp on said diaphragm, and an operating mechanism actuated from the diaphragm and responsive to the pressure on the diaphragm caused by the change of consistency in the pulp, said head having graduations, and a stationary scale carried by the body cooperating with the graduations on the head for indicating the position of the head relative to the orifice.

4. A consistency responsive apparatus for pulp comprising, a body having an inlet for receiving pulp and an outlet for the pulp, said body also having an orifice therein between the inlet and the outlet through which the pulp flows, a diaphragm on one side of the orifice, a head on the other side of the orifice to cause a frictional resistance to the flow of the pulp through the orifice and thereby create a pressure on the diaphragm, said diaphragm being movable under changes of pressure, an operating mechanism actuated by the diaphragm upon movement of the diaphragm by change of pressure, means for regulating the flow of the pulp to the body, and means for adjusting the position of the head relative to the orifice for controlling the active size of the orifice.

HERVEY G. CRAM.
